H. L. SCHERMERHORN

VARNISH TANK

Filed June 28, 1923

Inventor:
Harmon L. Schermerhorn,

by Alexander D. Hunt
His Attorney

UNITED STATES PATENT OFFICE.

HARMON L. SCHERMERHORN, OF SCHENECTADY, NEW YORK, ASSIGNOR TO GENERAL ELECTRIC COMPANY, A CORPORATION OF NEW YORK.

VARNISH TANK.

Application filed June 28, 1923. Serial No. 648,406.

My invention relates to tanks for varnish and the like, and has for its object the provision of condensing means which may be placed over a tank containing a volatile substance, as for instance a solvent which is being added to a varnish, to effectively prevent escape of the solvent in the form of vapor.

In the making of various kinds of varnishes, it is the practice to cook the various materials making up the body of the varnish together after which a suitable solvent, such as gasoline, is added to thin the mixture to the desired gravity. The gasoline or other solvent must be added while the prepared varnish is still at a high temperature and as a result rapid vaporization of the solvent takes place until the mixture has cooled somewhat. Obviously, when using an open tank this results in great waste of solvent and also a fire hazard due to the escaping vapors.

In carrying out my invention, I provide a condensing hood which may be placed over the varnish tank after the cooking operation has been completed whereby the solvent vapors are condensed and returned to the tank.

For a more complete understanding of my invention reference should be had to the accompanying drawing, the single figure of which is a section view of a condensing hood embodying my invention.

Referring to the drawing, the various ingredients forming the body of the varnish are mixed and cooked in a suitable tank 10. After the cooking has been completed a condensing hood 11 is placed over the tank and the solvent added. This condensing hood comprises a double walled, cone shaped portion 12 secured to the bottom of which is a cylindrical portion 13. The lower edge of portion 13 is provided with a flange 14 which rests on the upper edge of the tank 10 and forms a support for the condensing hood when it is placed over the tank. A suitable cooling liquid, such as water, is circulated through the chamber formed between the double walls of the conical portion 12 by means of inlet and outlet pipes 15 and 16.

In the interior of the hood are two baffles 17 and 18 somewhat smaller than the portions of the hood in which they are placed. The purpose of the baffles is to direct the

solvent vapors arising from the tank 10 against the cooled inner surface of the cone shaped portion 12. Also a certain amount of the vapors are condensed upon striking the lower baffle 17. This baffle is provided with a plurality of apertures 19 and with a central aperture 20. A stack or flue 24 is provided at the apex of the cone shaped portion 12. The solvent is added through a funnel 21 extending through the cylindrical portion 13 into the tank. Eyes 22 and 23 are provided to facilitate the handling of the hood.

In using the condensing hood, after the varnish ingredients have been cooked in the tank 10 the condensing hood is placed over the tank. Preferably this is done by moving the tank underneath the hood which is in raised position and then lowering the hood into place over the tank. The solvent is then added through the funnel 21 a large portion of which, due to the high temperature of the varnish, is immediately vaporized. The solvent vapors, however, are condensed by the hood and returned to the tank. Only a very small amount of the vapors remain uncondensed and escape through the stack 24. It is desirable to provide the stack to prevent the accumulation of vapors at the apex of the hood and resulting danger of explosions. The cone shaped baffles present inclined surfaces to the condensed vapors falling upon them and thus allow the condensate to freely return to the tank.

While I have described my invention as embodied in concrete form and as operating in a specific manner in accordance with the provisions of the patent statutes, it should be understood that I do not limit my invention thereto, since various modifications thereof will suggest themselves to those skilled in the art without departing from the spirit of my invention, the scope of which is set forth in the annexed claim.

What I claim as new and desire to secure by Letters Patent of the United States, is:—

The combination with a varnish cooking tank of a condensing hood arranged to be set on said tank after the completion of the cooking operation when the varnish solvents are being added, said hood comprising a double walled conical member forming a chamber through which a cooling liquid is

circulated, a lower conical baffle provided with apertures mounted in said conical member in spaced relation with the inner wall thereof, an upper conical baffle secured in spaced relation with the inner wall of said conical member whereby solvent vapors arising from said tank are directed against the cooled surface of said hood to be condensed,

the condensate falling upon the upper inclined surfaces of said baffles and being returned thereby to said tank, and a flue at the apex of said conical member.

In witness whereof, I have hereunto set my hand this 26th day of June, 1923.

HARMON L. SCHERMERHORN.
